END LINK FOR A WATCH BRACELET OR SIMILAR ARTICLE

Murray L. Cowan, Norwood, Mass., assignor to Textron
Inc., Providence, R.I., a corporation of Rhode Island

Filed June 23, 1965, Ser. No. 85,868

Term of patent 7 years

(Cl. D45—4)

FIG. 1

FIG. 2

FIG. 4

FIG. 1 is a top plan view of an end link for a watch bracelet or similar article, showing my new design;

FIG. 2 is a side elevational view;

FIG. 3 is an end elevational view on an enlarged scale looking from the left of FIG. 1; and

FIG. 4 is a perspective view thereof.

I claim:

The ornamental design for an end link for a watch bracelet or similar article, substantially as shown.
